CLAIM

The ornamental design for a generator motor recoil cover, as shown as described.

DESCRIPTION

FIG. 1 is a front perspective view of a generator motor recoil cover showing my new design;

FIG. 2 is a rear view of thereof;

FIG. 3 is a left side view of thereof;

FIG. 4 is a right side view of thereof;

FIG. 5 is a top plan view of thereof;

FIG. 6 is a bottom plan view of thereof; and,

FIG. 7 is a perspective view thereof.
